HAND LOOM

Harry Robertson Dillon, Niagara Falls, N. Y.

Application May 7, 1945, Serial No. 592,345

2 Claims. (Cl. 139—33)

1

This invention relates to an improvement in a weaving machine, and more particularly to weaving looms adapted to accommodate warp and weft loop threads, sometimes termed "looper clips."

In the medical field of occupational therapy, which is becoming more extensively practiced, various and sundry devices have been adapted for use in connection with the human hands. For sometime the art of hand weaving has played an extensive part in the aforesaid field; being used for bringing the human muscles into play by the exercise acquired from hand weaving.

One of the most widely utilized hand weaving devices, is a simple frame structure upon the edges of which are disposed pegs adapted to accommodate loop threads. However, this type of loom requires tedious threading of a hook or needle over and under the warp loops in order that a weft thread may be drawn through them.

One of the objects of this invention is the provision of a weaving machine or loom whereby the desired warp loop threads thereon may be actuated so as to provide a space through which a weft loop thread may be passed, and thereby eliminate the "over and under" or lacing method now practiced.

Another object of this invention is the provision of a weaving loom provided with movable pegs for elevating and lowering desired threads on said loom.

A further object of this invention is the provision of a weaving loom having certain movable pegs which facilitate the process of weaving, and thereby effect a saving of time in the making of woven articles.

Other objects and features will more fully appear from the following description and accompanying drawings in which: Fig. 1 is a top view; Fig. 2 a sectional end view taken along lines 2—2 of Fig. 1; Fig. 3 a side view; Fig. 4 a varied side view; and Fig. 5 a partial sectional end view.

Referring to the drawings the weaving machine or loom 1 consists of a frame 2 formed by sides 3—4 and ends 5—6. Upon the respective top edges of the sides are disposed a plurality of pegs 7 which are adapted to accommodate loop weft threads 8. The pegs on side 3 are equally spaced and paired with the pegs on side 4; which are likewise positioned.

End 5 is also provided with a plurality of pegs 9 disposed on the top edge thereof and also equally spaced. These pegs are adapted to provide an anchorage for warp loop threads 10.

A chamber 11 is disposed in end 6 and the top thereof is provided with a plurality of apertures

2

15. An upper carriage 12 is substantially housed in the chamber and is adapted for disposition upon supports 13 which are secured to the walls of said chamber. A plurality of pegs 14 are secured in upright fashion to carriage 12 and are in aligned spaced relation to each other as clearly disclosed in Fig. 2. Pegs 14 respectively register with and extend beyond the apertures 15 in the path of said pegs.

10 A basal carriage 16 is supported by the bottom of chamber 11, and its ends thereof project from said chamber, as do the ends of carriage 12. A plurality of pegs 17 are secured in upright fashion upon carriage 16 and are in alignment with and 15 equally spaced upon said carriage. Pegs 17 respectively register with and extend through orifices 18 in platform 12 and also apertures 15 which are coincident with orifices 18. Apertures 15 and orifices 18 are larger than pegs 14—17 thus permitting free movement therethrough.

Pegs 14 and 17 likewise are formed in alignment on the edge of end 6 and are directly opposed to pegs 9 on end 5; and the pegs on each of said ends are respectively equally spaced and 25 paired. Warp threads 10 are anchored to pegs 9 on end 5 and pegs 14—17 in end 6 as clearly disclosed in Fig. 1.

The device functions as follows: when carriage 12 (see Fig. 4) is elevated, pegs 14 rise and the 30 warp threads on each of these pegs also ascend, while the warp threads secured to pegs 17 remain in horizontal position. The threads on pegs 14 are therefore in spaced relation to the threads on pegs 17 and thus form an opening through 35 which one of the weft loop threads 8 may be drawn by a hook 20 and anchored respectively to pegs 7 nearest end 5.

It will therefore be noted (see Fig. 1) that by the foregoing operation the weft thread has been 40 woven over and under the warp threads by simply passing it through the said opening and sliding it under the elevated warp threads to its said anchorage point.

Carriage 12 is then lowered upon supports 13 45 and carriage 16 is elevated. The warp threads 10 on pegs 17 (see Fig. 3) are elevated while the threads on pegs 14 remain in horizontal position and it is therefore obvious that another opening is created and at the same time the weft 50 thread already anchored is locked. Another weft thread is passed through the opening and slid under the elevated warp threads 10 on pegs 17 and anchored to the pegs 7 which are second in line from end 5.

55 By repeating the foregoing operations in alter-

nate fashion the article to be woven is produced. The edges of the loop threads are then laced, as is well known in the art, and the woven material is completed.

The size of the woven article depends upon the size of the frame and number of pegs and this may be varied as required.

Warp threads 10 are elastic and the tension tends to pull pegs 14-17 toward pegs 9 thereby holding the pegs in the position they have been placed, without any support from the operative.

Pegs 9-7 are provided with caps to facilitate lacing the edges; since said caps keep the loop threads from coming off due to upward pull in the lacing operation.

Having described this invention, what is claimed is:

1. In a device of the character described consisting of a frame provided with two sides and two ends; a plurality of pegs on two of said sides and one of said ends for the reception of a material to be woven; the other of said ends provided with a chamber, an upper platform and a lower platform housed in said chamber and being independently vertically movable therein, a plurality of pegs on said upper and lower platforms for the reception of material to be woven, said other end being provided with guide apertures for the passage of said plurality of pegs on said platforms, and said upper platform having apertures

for the passage of the pegs of the lower platform, and means for supporting said upper platform.

2. In a device of the character described consisting of a frame provided with two sides and two ends; a plurality of pegs on the two sides and one of the two ends for the reception of a material to be woven; the other of said ends provided with a chamber, independently movable platforms housed in said chamber, a plurality of pegs on each of said platforms for the reception of material to be woven, said other end being provided with guide apertures for the passage of said plurality of pegs on said platforms.
